UNITED STATES PATENT OFFICE.

WALTER A. WAGNER, OF SHEBOYGAN, WISCONSIN.

HAME.

1,170,713.

Specification of Letters Patent.

Patented Feb. 8, 1916.

Application filed April 8, 1914. Serial No. 830,436.

To all whom it may concern:

Be it known that I, WALTER A. WAGNER, a citizen of the United States, residing at Sheboygan, in the county of Sheboygan and 5 State of Wisconsin, have invented certain new and useful Improvements in Hames, of which the following is a specification.

This invention relates to improved hames, and the principal object is to provide an 10 improved attachment with the hames so that the fastening strap for the top of the hames may have a relatively large amount of adjustment.

Another object of the invention is to so 15 construct the plate that it may be connected with hames now in use without the hames needing to be altered in order to connect the plate with them.

These objects are accomplished by providing 20 the plate with strap receiving openings positioned at a certain angle as will be brought out farther on, thus permitting a relatively large number of openings to be formed in each of the plates without the 25 plates being weakened.

This invention is illustrated in the accompanying drawings wherein—Figure 1 is a side elevation of a hame provided with the improved plate; Fig. 2 is a transverse sectional view taken along the line 2—2 of 30 Fig. 1.

The hame 10 is constructed similar to hames which are now in use, and is provided with the usual bottom piece 11 by 35 means of which the lower ends of a pair of hames may be connected, and with the usual ornamental knob 12 at its upper end. The plate 13 is provided with reduced upper and lower end portions 14 and 15 through 40 which securing screws or bolts 16 are passed to connect the plate with the upper end por-

tion of the hame. Slots 17 are formed in the plate 13 and are cut at an incline as shown at Fig. 1 with their end portions overlapping. By having the slots cut at an 45 incline with their end portions overlapping, a relatively large number of slots may be formed in the plate 13 without the plate being weakened and without the plate being unnecessarily elongated, therefore the 50 strap which connects the ends of the hames may be adjusted without it being moved a very great distance along the plate. This permits the strap to be adjusted longitudinally of the plates a short distance. 55

It will thus be seen that I have provided an attachment by means of which the connecting straps may be adjusted a small amount; and that I have also provided a plate which will permit of this adjustment 60 without the plate being unnecessarily weakened. It should also be noted that this plate can be formed of sheet metal or cast metal, or can be formed of any other suitable material such as wood or composition. 65

What is claimed is:

An attachment for hames comprising a plate having its end portions reduced to provide upper and lower extensions, each of the extensions being provided with a fastener receiving opening, the body portion of the plate between the extensions being provided with diagonally extending slots having their end portions positioned in overlapping relation. 70 75

In testimony whereof I affix my signature in presence of two witnesses.

WALTER A. WAGNER.

Witnesses:

JOHN M. DETLING,
LYDIA E. ZERLER.
